UNITED STATES PATENT OFFICE.

WILLIAM HARDICK, OF CADILLAC, AND LEROY A. OGDEN, OF GRAND RAPIDS, MICHIGAN, ASSIGNORS OF ONE-THIRD TO GEORGE JOHNSTON, OF CADILLAC, MICHIGAN.

SWITCH-THROW.

1,110,626.

Specification of Letters Patent. Patented Sept. 15, 1914.

Application filed June 16, 1913. Serial No. 774,014.

To all whom it may concern:

Be it known that we, WILLIAM HARDICK and LEROY A. OGDEN, citizens of the United States, residing respectively at Cadillac and Grand Rapids, in the counties of Wexford and Kent, State of Michigan, have invented a new and useful Switch-Throw, of which the following is a specification.

The device forming the subject matter of 10 this application is a means whereby the doors of a switchman's cage may be controlled during the operation which terminates in a throwing of the switch point.

The invention aims to provide novel 15 means whereby the door of the switchman's cage will be closed and opened during the operation which terminates in the throwing of the switch point, the end in view being primarily to prevent the switchman from 20 leaving the cage while the switch point is set for a siding.

It is within the scope of the invention to 25 improve generally and to enhance the utility of devices of that type to which the present invention appertains.

With the above and other objects in view 30 which will appear as the description proceeds, the invention resides in the combination and arrangement of parts and in the details of construction hereinafter described and claimed, it being understood that changes in the precise embodiment of the invention herein disclosed can be made 35 within the scope of what is claimed without departing from the spirit of the invention.

In the drawings:—Figure 1 shows in 40 vertical longitudinal section, a switchman's cage to which the present invention has been applied, parts appearing in elevation; Fig. 2 is a perspective showing a portion of the actuating shaft and the parts carried thereby; Fig. 3 is a fragmental top plan showing a portion of the mechanism whereby an unauthorized opening of the door of 45 the switchman's cage is prevented; Fig. 4 is a top plan of the cage and the mechanism contained therein; Fig. 5 is a transverse section through the top of the switch stand on the line 5—5 of Fig. 1; Fig. 6 is a perspective detail illustrating the inner and outer tubes which are carried by the actuating shaft; Figs. 7 and 8 are diagrammatic 50 views alluded to in that portion of this

specification wherein the operation of the device is set forth.

In carrying out the invention there is provided a switchman's cage 1 within which is located a switch stand 2. The invention includes an actuating shaft 3, preferably disposed vertically, the lower end 4 of the actuating shaft 3 being of circular contour and being journaled for rotation in the switch stand 2. Secured to the lower end 4 of the actuating shaft 3 is an arm 5 or other suitable mechanism, connected with a link 6, 60 the link constituting means whereby the switch point is actuated directly.

Throughout the major portion of its length, the actuating shaft 3 is square as indicated at 7. Referring particularly to Fig. 70 5, the top of the switch stand 2 is denoted by the numeral 8 and is provided with a squared socket 9 adapted to receive the lower end of a correspondingly shaped head 10, the head 10 receiving slidably, but 75 against relative rotation, the squared portion 7 of the actuating shaft 3. A lever 11 is fulcrumed intermediate its ends, as shown at 12 upon the head 10 and suitable latch mechanism 14 of any sort is mounted upon 80 the switch stand 2, to coöperate with the lever 11 when the same is in the depending position shown in Fig. 1. Links 15 connect the lever 11 with a collar 16 which is journaled for rotation upon the upper end 8 of 85 the switch stand 2.

The invention includes an inner tube 17 mounted to rotate upon the actuating shaft 3 and to slide longitudinally thereon, the tube 17 being equipped at its upper end 90 with a transversely extended head 18 co-operating with a hollow head 19 upon an outer tube 20, the tube 20 surrounding the tube 17 and being mounted to slide and to rotate thereon. A link 21 pivotally connects 95 the lever 11 with the outer tube 20. There is a slot 22 in the top 23 of the head 19 which constitutes a part of the outer tube 20, and the inner tube 17 is equipped with a projection 24, adapted to pass through the 100 slot 22 and to engage beneath the top 23 of the head 19. At its upper end, the shaft 3 carries signals 25 of any desired form. Mounted upon the squared portion 7 of the shaft 3 adjacent the upper end of the shaft 105 105 is a transversely extended arm 26, the arm

in the present instance being shown as provided with a socket 27 inclosing the squared portion 7 of the shaft 3 and held thereon by a set screw 28. The function of the arm 26 will be set forth hereinafter.

The switchman's cage 1 is equipped with one or more doorways 29 controlled by doors 30 which may be mounted to move in any desired manner. In the present instance, the doors 30 are shown as equipped with hangers 31 engaging tracks 32 upon the cage 1, the doors being held by cage-supported keepers 33. Adjacent its upper end, the cage 1 supports bearings 34 in which is journaled for rotation a transverse counter-shaft 35 having depending primary arms 36 equipped at their lower ends with elongated slots 37 receiving studs 38 mounted upon the doors 30. Intermediate its ends, the counter-shaft 35 is provided with a secondary arm 39 which projects in an opposite direction from the arms 36. As shown to best advantage in Fig. 2, the secondary arm 39 is equipped with a slot 40 receiving a pin 41 outstanding from the inner tube 17.

Let it be assumed that the doors 30 are open as shown in Fig. 1 and as indicated diagrammatically at 45 in Fig. 7, the numeral 42 indicating the main rails, the numeral 43 indicating the siding rails and the numeral 44 indicating the switch point. Then the operation of the device is as follows:

The switch man enters the cage 1 and elevates the lever 11. When the lever 11 is elevated, the lower end of the squared head 10 is lifted out of the squared socket 9 in the part 8 of the switch stand 2. When the lever 11 is elevated, the link 21 will elevate the outer tube 20, the top 23 of the head 19 of the tube 20 abutting against the head 18 of the inner tube 17. In this manner, when the lever 11 is elevated, the inner tube 17 will be elevated also, and the pin 41, moving in the slot 40 of the secondary arm 39 will impart rotation to the shaft 35, the primary arms 36 being actuated and the doors 30 being swung to a closed position. By this operation, the switch man will be imprisoned within the cage 1 and in this connection it is to be noted that the arm 26 which is carried by the squared portion 7 of the shaft 3 is adapted to engage beneath the secondary arm 39 upon rotation of the switch stand mechanism and 55 lock the doors 30 in closed positions.

The lever 11 is then swung through an angle of 90°, the head 10 being rotated, and rotatory movement being imparted to the actuating shaft 3, because the squared portion 7 of the actuating shaft is engaged within the head 10, as clearly shown in Fig. 5. During the operation above described the collar 16 will rotate upon the upper end 8 of the switch stand 2. When the shaft 3 is thus rotated, the crank arm 5 which

is secured to the lower end of the shaft 3 will impart movement to the link 6 and to the switch point 44, so that the same assumes an open position with respect to the main line 42, as shown in Fig. 8, the doors 30 of the switchman's cage having been closed, as indicated at 47 in Fig. 8.

When the outer tube 20 is rotated through the action of the lever 11, the slot 22 will be moved until the same is in alinement 75 with the pin or projection 24 which stands from the inner tube 17. If the lever 11 be depressed, the head 10 will engage again with the socket 9, the slot 22 permitting relative sliding movement between the tube 20 and the tube 17, so that the parts appear as shown in Fig. 6. The switch point is now set for the siding, as shown in Fig. 8, the doors are held closed as shown at 47 and the switchman is within the cage. 85 It is therefore obvious that before the switchman can leave the cage 1, the parts must be returned to the positions shown in Fig. 1 and the switch point must be set as indicated at 44 in Fig. 7. Thus, it is impossible for the switchman to leave his post when the switch point is set for the siding.

In order to open the doors 30 as shown at 45 and to restore the switch point to the position indicated at 44 in Fig. 7, the lever 11 is raised and swung horizontally to its original position and depressed. This operation will bring the head 19 into engagement with the head 18 and when the tube 20 is rotated, the projection 24 will 100 assume a position to one side of the slot 22 and beneath the top 23 of the head 19. Therefore, when the lever 11 is swung downwardly and when the outer tube 20 is depressed also, the arm 39 and the shaft 35 being actuated, the parts being restored to the position shown in Fig. 1.

When the doors 30 are moved to a closed position, the arm 26, upon a rotation of 110 the shaft 3 engages beneath the arm 39. Recalling that the tubes 17 and 20 are in the positions shown in Fig. 6, it will be seen that the arm 26, being engaged beneath the arm 39, prevents the tube 17 115 from being slid downwardly within the tube 20, through a manual manipulation of the arm 39. The switchman, therefore, cannot open the doors while the switch point is in the position shown in Fig. 8—that is, 120 while the switch point is set for the siding.

Having thus described the invention, what is claimed is:—

1. In a device of the class described, a switchman's cage having a movable door; door operating means; switch throwing means; coacting members, one of which is operatively connected to the door operating means, the other of which is operatively connected to the throwing means; a locking 125

device interengaging elements on said co-acting members, said members being relatively movable to permit the throwing means to engage the locking device; and a member adapted to engage the door operating means to hold the door closed, the last specified member being operatively connected with the throwing means.

2. In a device of the class described, a switchman's cage having a movable door; door operating means; an actuating shaft; an arm on the shaft adapted to engage the door operating means to hold the door closed; a member movable upon the shaft and connected with the door operating means, to close the door and to bring the door operating means into the path of the arm; means for connecting the shaft to a switch point; and mechanism for simultaneously operating the shaft and actuating said member.

3. In a device of the class described, an actuating shaft; a pair of independently movable tubes upon the shaft; interengaging elements upon the tubes; door operating

mechanism connected with one tube; means for connecting the shaft with a switch point; and shaft actuating means operatively connected with the other tube to move the same.

4. In a device of the class described, an actuating shaft; means for connecting the shaft with a switch point; a switchman's cage having a movable door; door operating means; a member movable upon the shaft and operably connected with the door operating means; a member on the shaft, coöperating with the door operating means to hold the door closed; a switch throwing mechanism operatively connected with the shaft and with said movable member.

In testimony that we claim the foregoing as our own, we have hereto affixed our signatures in the presence of two witnesses.
